UNITED STATES PATENT OFFICE

RAMIRO CORCES, OF TAMPA, FLORIDA, ASSIGNOR OF ONE-HALF TO J. A. PRIETO, OF MIAMI, FLORIDA

CIGAR MOLD

Application filed April 14, 1931. Serial No. 530,067.

This invention relates to a cigar mold and more particularly to a device of this character which is for use in compressing and shaping a cigar bunch and has for one of its important objects to provide, in a manner as hereinafter set forth, a mold embodying a novel construction and arrangement of parts whereby the bunch may be expeditiously placed therein and removed therefrom.

Other objects of the invention are to provide a cigar mold of the character described which will be simple in construction, strong, durable, efficient and reliable in operation and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation showing the cigar mold in accordance with this invention in open position.

Figure 2 is a view in vertical longitudinal section through the cigar mold showing the same in closed position.

Figure 3 is a view in horizontal section taken substantially on the line 3—3 of Figure 2 looking downwardly, as indicated by the arrows.

Figure 4 is a view in horizontal cross section taken substantially on the line 4—4 of Figure 2 looking downwardly, as indicated by the arrows.

Figure 5 is a view in top plan of the mold sections in closed position.

Figure 6 is a detail view in perspective of one of the springs which yieldingly urge the mold sections toward open position.

Referring now to the drawings in detail, it will be seen that the reference numeral 1 designates a base having arranged in a circle thereon the pairs of upstanding, apertured

ears 2. A plurality of complementary mold sections 3 of substantially segmental cross section are provided with vertical ribs 4 on their outer sides which project below the sections 3 and are pivotally connected between the pairs of ears 2, as at 5. Intermediate portions of the ribs 4 are recessed in a manner to provide the inclined or cam surfaces 6 and the horizontally disposed shoulders 7, the purpose of which will be presently set forth.

The inner sides of the mold sections 3 are channeled or formed to provide a chamber 8 of the desired shape when the mold sections are in closed position. It will be noted that the chamber 8 is restricted at its ends. The chamber 8 is, of course, for the reception of the cigar bunch.

The sections 3 of the mold are also provided with the outwardly extending longitudinal marginal flanges 9 which are disposed in opposed relation to each other when the mold sections are in closed position. Secured in any suitable manner to the inner walls of the mold sections 3 which define the bunch receiving chamber 8 is a layer of suitable compressible material, such as cork, 10, over which is disposed a lining of suitable flexible material such as leather, 11. The leather lining 11 extends outwardly over the longitudinal edges of the sections of cork 10 and the marginal portions of said leather lining are secured in any suitable manner to the opposed sides of the flanges 9 in the manner illustrated to advantage in Figure 3 of the drawings. In this manner the marginal portions of the leather lining provide a cushion between the mold sections and, as will be apparent, the lining 11 and the compressible layers 10 prevent excessive compressing of the cigar bunch in the mold.

A standard 12 is mounted on the base 1 and is provided with a bifurcated upper end portion in which is pivotally mounted for swinging movement in a vertical plane a lever 13 having a handle portion on one end a yoke 14

on its other end in which is pivotally mounted a clamping ring 15 which encircles the mold sections 3 and which is vertically slidable over the cam surfaces 16 in a manner to swing the mold sections toward their closed position upon upward movement of the clamping ring. The clamping ring is internally tapered as at 16. Springs 17 are mounted on the base portions of the apertured ears 2 and are operatively engaged with the downwardly extending lower end portions of the ribs 4 in a manner to yieldingly urge the mold sections 3 away from each other toward their open position. It may be well to here call attention to the fact that the clamping ring 15 is engageable for rest on the shoulders 7 when in its lowered or inoperative position and when the mold sections 3 are in their open position, as illustrated to advantage in Figure 1 of the drawings.

Toothed perforating plates 18 are mounted, through the medium of screws 19, on the upper ends of the mold sections 3 for the purpose of perforating the head or upper end portion 25 of the cigar bunch to facilitate the breaking off thereof when the mold sections 3 are in closed or operative position. Ears 20 depend from the outer end portions of the perforating plates 18 on opposite sides of the upper 30 end portions of the ribs 4 for retaining the perforating plates against rotation around the screws 19.

It is believed that the many advantages of a cigar mold constructed in accordance with 35 the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A cigar mold comprising a base, a plurality of complementary mold sections mounted for swinging movement toward and away from each other on the base, said mold sections having their inner walls recessed in a manner to define a chamber for the reception of a cigar bunch when the mold sections are in closed position, and means for opening and closing the mold sections, said means including a ring slidably encircling the sections and operatively engaged therewith for simultaneously swinging said sections toward each other.

2. A cigar mold comprising a base, a plurality of complementary mold sections mounted for swinging movement toward and away from each other on the base, said mold sections having their inner walls recessed in a manner to define a chamber for the reception of a cigar bunch when the mold sections are in closed position, and means for opening and closing the mold sections, said means

comprising cams extending longitudinally on the outer sides of the mold sections, a ring encircling the mold sections for longitudinal movement relative thereto and operatively engageable with the cams in a manner to swing the mold sections toward each other upon movement of the ring in one direction, and a lever pivotally mounted on the base and connected with the ring for actuating said ring.

3. A cigar mold comprising a base, a plurality of complementary mold sections mounted for swinging movement toward and away from each other on the base, said mold sections having their inner walls recessed in a manner to define a chamber for the reception of a cigar bunch when the mold sections are in closed position, and means for opening and closing the mold sections, said means comprising cams extending longitudinally on the outer sides of the mold sections, a ring encircling the mold sections for longitudinal movement relative thereto and operatively engageable with the cams in a manner to swing the mold sections toward each other upon movement of the ring in one direction, and a lever pivotally mounted on the base and connected with the ring for actuating said ring.

4. A cigar mold comprising a base, a plurality of complementary mold sections mounted for swinging movement toward and away from each other on the base, said mold sections having their inner walls recessed in a manner to define a chamber for the reception of a cigar bunch when the mold sections are in closed position, and means for opening and closing the mold sections, said means comprising cams extending longitudinally on the outer sides of the mold sections, a ring encircling the mold sections for longitudinal movement relative thereto and operatively engageable with the cams in a manner to swing the mold sections toward each other upon movement of the ring in one direction, and a lever pivotally mounted on the base and connected with the ring for actuating said ring.

5. A cigar mold comprising a base, a plurality of complementary mold sections mounted for swinging movement toward and away from each other on the base, said mold sections having their inner walls recessed in a manner to define a chamber for the reception of a cigar bunch when the mold sections are in closed position, and means for opening and closing the mold sections, said means comprising cams extending longitudinally on the outer sides of the mold sections, a ring encircling the mold sections for longitudinal movement relative thereto and operatively engageable with the cams in a manner to swing the mold sections toward each other upon movement of the ring in one direction, and a lever pivotally mounted on the base and connected with the ring for actuating said ring.

6. A cigar mold comprising a base, a plurality of complementary mold sections mounted for swinging movement toward and away from each other on the base, said mold sections having their inner walls recessed in a manner to define a chamber for the reception of a cigar bunch when the mold sections are in closed position, and means for opening and closing the mold sections, said means comprising cams extending longitudinally on the outer sides of the mold sections, a ring encircling the mold sections for longitudinal movement relative thereto and operatively engageable with the cams in a manner to swing the mold sections toward each other upon movement of the ring in one direction, and a lever pivotally mounted on the base and connected with the ring for actuating said ring.

7. A cigar mold comprising a base, a plurality of complementary mold sections mounted for swinging movement toward and away from each other on the base, said mold sections having their inner walls recessed in a manner to define a chamber for the reception of a cigar bunch when the mold sections are in closed position, and means for opening and closing the mold sections, said means comprising cams extending longitudinally on the outer sides of the mold sections, a ring encircling the mold sections for longitudinal movement relative thereto and operatively engageable with the cams in a manner to swing the mold sections toward each other upon movement of the ring in one direction, and a lever pivotally mounted on the base and connected with the ring for actuating said ring.

8. A cigar mold comprising a base, a plurality of complementary mold sections mounted for swinging movement toward and away from each other on the base, said mold sections having their inner walls recessed in a manner to define a chamber for the reception of a cigar bunch when the mold sections are in closed position, and means for opening and closing the mold sections, said means comprising cams extending longitudinally on the outer sides of the mold sections, a ring encircling the mold sections for longitudinal movement relative thereto and operatively engageable with the cams in a manner to swing the mold sections toward each other upon movement of the ring in one direction, and a lever pivotally mounted on the base and connected with the ring for actuating said ring.

to move said mold sections toward each other in a manner to compress and shape the cigar bunch into shape, said chamber being open at its ends, toothed perforating plates 5 mounted on the free ends of the mold sections and extending over the chamber for perforating the adjacent end portion of the bunch when the mold sections are closed, and springs operatively engaged with the mold sections for yieldingly urging said mold sections away from each other.

In testimony whereof I affix my signature.
RAMIRO CORCES.
